(57) **CLAIM**

The ornamental design for an display screen with an animated avatar, as shown and described.

DESCRIPTION

FIG. 1 is a front view of the first image in the sequence for a display screen with an animated avatar showing our new design;

FIG. 2 is a front view of the second image thereof;

FIG. 3 is a front view of the third image thereof; FIG. 4 is a front view of the fourth image thereof; FIG. 5 is a front view of the fifth image thereof; FIG. 6 is a front view of the sixth image thereof; FIG. 7 is a front view of the seventh image thereof; FIG. 8 is a front view of the eighth image thereof; FIG. 9 is a front view of the ninth image thereof; FIG. 10 is a front view of the tenth image thereof; FIG. 11 is a front view of the eleventh image thereof; FIG. 12 is a front view of the twelfth image thereof; FIG. 13 is a front view of the thirteenth image thereof; FIG. 14 is a front view of the fourteenth image thereof; FIG. 15 is a front view of the fifteenth image thereof; FIG. 16 is a front view of the sixteenth image thereof; FIG. 17 is a front view of the seventeenth image thereof; FIG. 18 is a front view of the eighteenth image thereof; FIG. 19 is a front view of the nineteenth image thereof; FIG. 20 is a front view of the twentieth image thereof; FIG. 21 is a front view of the twenty-first image thereof; FIG. 22 is a front view of the twenty-second image thereof; FIG. 23 is a front view of the twenty-third image thereof; FIG. 24 is a front view of the twenty-fourth image thereof; FIG. 25 is a front view of the twenty-fifth image thereof; FIG. 26 is a front view of the twenty-sixth image thereof; FIG. 27 is a front view of the twenty-seventh image thereof; FIG. 28 is a front view of the twenty-eighth image thereof; FIG. 29 is a front view of the twenty-ninth image thereof; FIG. 30 is a front view of the thirtieth image thereof; FIG. 31 is a front view of the thirty-first image thereof; FIG. 32 is a front view of the thirty-second image thereof;

FIG. 33 is a front view of the thirty-third image thereof; FIG. 34 is a front view of the thirty-fourth image thereof; FIG. 35 is a front view of the thirty-fifth image thereof; FIG. 36 is a front view of the thirty-sixth image thereof; FIG. 37 is a front view of the thirty-seventh image thereof; FIG. 38 is a front view of the thirty-eighth image thereof; FIG. 39 is a front view of the thirty-ninth image thereof; FIG. 40 is a front view of the fortieth image thereof; FIG. 41 is a front view of the forty-first image thereof; FIG. 42 is a front view of the forty-second image thereof; FIG. 43 is a front view of the forty-third image thereof; FIG. 44 is a front view of the forty-fourth image thereof; FIG. 45 is a front view of the forty-fifth image thereof; FIG. 46 is a front view of the forty-sixth image thereof; FIG. 47 is a front view of the forty-seventh image thereof; FIG. 48 is a front view of the forty-eighth image thereof; FIG. 49 is a front view of the forty-ninth image thereof; FIG. 50 is a front view of the fiftieth image thereof; FIG. 51 is a front view of the fifty-first image thereof; and, FIG. 52 is a front view of the fifty-second image thereof. The appearance of the animated avatar sequentially transitions between the images shown in FIGS. 1-52. The process or period in which one image transitions to another forms no part of the claimed design. The broken line showings of a portion of the display screen, seat back, and portions of the avatar are for the purpose of illustrating unclaimed portions of the display screen with an animated avatar and form no part of the claimed design.
